FISH SCALER

Daniel H. Brown, 107 S. Jonesville Blvd., Jonesville, N.C. 28642, and Joseph R. Brown, P.O. Box 6273, Greensboro, N.C. 27405

Filed Apr. 24, 1975, Ser. No. 571,277

Term of patent 14 years

Int. Cl. D22—05

U.S. Cl. D22—31

FIG. 1

FIG. 2

FIG. 3

FIG. 1 is a front perspective view of a fish scaler embodying our design;

FIG. 2 is a longitudinal side view of FIG. 1; and

FIG. 3 is a bottom plan view.

The broken lines are for illustrative purposes only.

We claim:

The ornamental design for a fish scaler, as shown and described.
